UNITED STATES PATENT OFFICE.

CLIFTON D. PETTIS, OF NEW YORK, N. Y.

CASTING MOLD.

REISSUED

Application filed March 2, 1923. Serial No. 622,262.

To all whom it may concern:

Be it known that I, CLIFTON D. PETTIS, a citizen of the United States, residing at New York city, New York, have invented 5 certain new and useful Improvements in Casting Molds, of which I do declare the following to be a full, clear, and exact description, reference being had to the accompanying drawings, forming a part of this 10 specification.

The present invention has for its object to provide an effective construction of casting mold whereby brake shoes or other articles ordinarily made of cast metal can be formed.

15 The invention consists in the features of novelty hereinafter described, illustrated in the accompanying drawings and particularly pointed out in the claims at the end of this specification. As will hereinafter more 20 fully appear, the invention relates more particularly to that class of casting molds designed to be repeatedly used in the casting operation and commonly designated as "permanent molds."

25 Figure 1 is a view in side elevation of a casting mold embodying my invention. Figure 2 is a view in end elevation. Figure 3 is a view in vertical longitudinal section. Figure 4 is a view in vertical cross section 30 on line 4-4 of Fig. 3. Figure 5 is a view in vertical cross section on line 5-5 of Fig. 3.

35 A designates the base, preferably formed of cast metal, whereon my improved casting mold will be mounted. In the embodiment of the invention illustrated in the drawings, my improved casting mold is shown as comprising a plurality of separable sections or members pivotally mounted upon the base 40

45 A and forming a flask or holder, each member carrying a corresponding part of the molding receptacle. To this end, the base A is formed with upstanding lugs 6 at each side of its center, through which lugs passes a pivot rod 7, this rod passing also through lugs or ears 8 depending from the bottom of the lower side members B. These lower side members B are pivotally mounted upon opposite sides of a centrally arranged station-

50 ary bar or support A² that rises from and is preferably cast integral with the base A. Each of the lower members B has pivotally connected thereto an upper side member C, the pivoting of these upper and lower side 55 members being conveniently effected by a

pivot rod 10 that passes through the lugs 11 of the lower side member and the lugs 12 of the upper side member, as clearly shown in Figs. 1 and 2 of the drawings.

From the base of the members D which 60 form the ends of my improved mold, depend lugs 13 through which pass the pivot rods 14, the ends of these rods passing also through the upstanding lugs 15 that rise from the base A and may be cast integral 65 therewith. This arrangement enables the end members D to swing about the pivot rods 14 when the mold is to be opened or closed. When the members are in closed position, as shown in full lines on the drawings, they may be retained in such position by suitable hooks 16, the free ends of which engage the pins 17 projecting outwardly 70 from the upper side members C adjacent their ends.

75 In the preferred form of my invention, each of the members B, C and D is formed as a hollow casting, the outer walls of these members being perforated as at 18 to allow 80 free circulation of air around the exterior of the molding receptacle, to be presently described.

85 The molding receptacle is preferably formed of carborundum or some like refractory material that may be molded in the form of blocks and that will offer great resistance to the intense heat of the metal to be cast. In the preferred embodiment of the invention, the walls of the molding receptacle are formed in sections, each composed 90 of a plurality of these blocks of refractory material that are of such construction that they can be readily assembled in the several members of the flask or holder. Thus, the bottom section of the molding receptacle is 95 shown as comprising a series of blocks E mounted upon a longitudinally extending plate or support A¹ that may be formed integrally at its center with the upright lug or support A² and may have its ends integral with the upright lugs A⁴ that rise from the base A (see Figs. 3, 4 and 5). A key or guard plate A⁵ is formed with a rib 22 that enters a corresponding groove in the side walls of the blocks E, this key being 100 preferably formed also with a longitudinal rib 23 below the rib 22. The opposite walls of the blocks E (see Fig. 4) are formed with similar grooves to receive the rib 21 formed on the supporting plate A¹. After the blocks 110

E have been placed upon the support A¹, the key A³ will be placed in the position shown in Figs. 4 and 5 of the drawings, so as to interlock with the blocks E, and the key 5 A³ will then be securely held in place by the screws 24, as shown in Fig. 4 of the drawings, the position of these screws being indicated also by dotted lines in Fig. 3 of the drawings.

10 Each of the lower side members B is formed at its top as shown with an inwardly projecting bar or support 25 having at its inner end a longitudinal rib 26 and having also a depending rib 27. The 15 support 25 engages the blocks F constituting a part of the molding receptacle. These blocks F are formed in their upper portions with grooves to receive the ribs 26 and their lower portions are correspondingly shaped 20 to engage the ribs 28 on the key or guard plates 30. In assembling the blocks F, their upper portions are first placed in engagement with the ribs 26 of the supports 25, after which the key or guard plates 30 will 25 have their ribs 28 placed in engagement with the corresponding grooves in the blocks F and will then be secured to the lower side members B by screws 32, as indicated in Fig. 4 of the drawings.

30 As shown, each of the upper side members is provided with an inwardly projecting support 33 having a longitudinal rib 34 for engagement with the blocks G of refractory material that constitute the upper portion 35 of the molding receptacle. The blocks G have their upper edges shaped to engage the ribs 34 of the supports 33 and have their lower edges correspondingly shaped to engage with the ribs 36 on the key or guard 40 plates 38. When the blocks G have been assembled as shown, with their upper ends interlocking with the supports 33, the key or guard plates 38 will be engaged with the lower edges of the blocks G and will 45 then be secured to the inwardly projecting lugs 39 of the members C by screws indicated by dotted lines 40 (see Fig. 4). When the blocks of refractory material constituting the bottom and side walls of the molding 50 receptacle are assembled, as shown in the drawings, these blocks completely protect the metal parts of the flask from contact with the molten metal delivered to the casting chamber.

55 Each of the end members D is formed preferably of a hollow casting with perforations in its outer walls to freely admit air and each of these members D is provided adjacent its bottom with an upstanding 60 support 42 to receive the blocks H of refractory material, the supports 42 each having a longitudinal rib 43 to engage a corresponding groove formed in the lower edges of the blocks H. At its top, each of the 65 members D is provided with a key or guard

plate 44 having at its lower edge a rib 45 to engage a corresponding groove formed in each of the blocks H of refractory material. When these blocks H have been set in position upon the supports 42, as shown in Fig. 3 of the drawings, the key plates 44 will be arranged as shown, so that their ribs 45 will engage the upper edges of the blocks H. The key plates 44 may be formed with outwardly extending lugs or flanges 46, through 75 which screws (indicated by dotted lines) may be passed to connect the keys or guard plates 44 to lugs 47 projecting inwardly from the wall of the members D.

By reference to Figs. 3 and 5 of the drawings, it will be seen that each of the members C is formed with an inclined curved depending web or part 50 adapted to receive a corresponding half-conical block K of refractory material, these blocks K forming the pouring gate of the mold and meeting upon the parting line of the members C. Each of the curved depending parts 50 will be integral with the support 33 formed in the corresponding member C and will be provided at its lower end with a rib 51 corresponding with the rib 34 on such support 33. The blocks G of refractory material in those portions of the members C opposite the depending parts 50 95 will be molded to proper shape to engage the lower ends of such parts 50, as indicated in Figs. 3 and 5 of the drawings, and these blocks G will also be molded with semi-cylindrical openings through which the cast metal may pass from the pouring gates to the interior of the casting chamber.

In the accompanying drawings, my improved casting mold is shown as of a shape specifically adapted for the casting of brake 105 shoes for railway cars, although obviously the invention is equally applicable for the casting of any other articles.

One object in forming the molding receptacle of a plurality of blocks or sections is 110 to avoid the danger of the breakage of this receptacle or of the flask or holder therefor incident to the expansion when the cast metal is poured therein. This object I have accomplished by forming the molding receptacle of such number of refractory blocks that the spaces between the blocks, while not large enough to permit the passage of molten metal therethrough, will nevertheless take care of the expansion of the blocks and so 115 avoid the danger of breakage incident to such expansion. I am aware that materials when subjected to high temperatures have a definite co-efficient of expansion, say 1/8th of an inch per lineal foot; hence if the molding receptacle were made in one piece and one foot long, the longitudinal expansion of the receptacle would amount to approximately 1/8th of an inch during the operation of casting. I am also aware that molten metal 120

by reason of its viscosity will not flow through a small opening, say less than 1/64th of an inch wide. I would in such a case employ the blocks in such number that 5 the width of the individual spaces between the blocks would not exceed 1/64th of an inch and the spaces would be in sufficient number of aggregate at least 1/8th of an inch and so take care of the maximum 10 expansion of the blocks. While the spaces between the blocks are not of sufficient width to permit the passage of molten metal therethrough, they nevertheless effectively serve for the venting of the gases from the molten 15 metal during the casting operation. This eliminates the necessity for a riser or venting gate. It will be understood that when the blocks are set in position upon their respective supports, they will be held properly 20 spaced apart by the several key or guard plates hereinbefore described.

A further advantage incident to forming the molding receptacle of a plurality of sections of blocks of refractory material is that 25 the individual sections or parts of the receptacle can be readily replaced when required. By permitting a free circulation of air about the outer wall of the molding receptacle, the heat rapidly radiates therefrom. 30 This is a very advantageous feature.

The brake shoe *W* shown as in the casting chamber in Fig. 3 of the drawings is of a familiar type, being formed with the usual center lug *w* and end lugs *w'*, the center lug *w* having an opening that will be formed by a core supported in pockets *X*. It will be understood, of course, that the inner faces of the blocks of refractory material will be properly shaped to form such parts as the center lug *w* and end lugs *w'*; and where it is desired to form a brake shoe having certain areas chilled, cast iron blocks would preferably be used at such points of the molding receptacle, instead of the blocks of refractory material. 45

From the foregoing description, it will be seen that when the casting mold has its several parts in closed position as shown, the cast metal will be delivered through the 50 pouring gate into the casting chamber, the gases from the molten metal being vented through the spaces between the blocks of refractory material that compose the molding receptacle. It is highly desirable that the 55 casting should be quickly removed from the mold as soon as it is sufficiently set and my improved construction of mold enables the mold members to be freely turned away from the casting without scraping or sliding 60 against the casting.

While I have found it advantageous to form my blocks of carborundum or other highly refractory material, I am aware that metal or any other suitable substance can be

used and I do not wish to be limited to any 65 particular material or group of materials.

I claim as my invention:

1. A casting mold having a molding receptacle comprising a plurality of blocks of refractory material, said blocks being spaced 70 apart to permit the expansion of the blocks, the spaces between the blocks being of such width as to prevent the passage of molten metal therethrough while allowing for the escape of gases from said metal. 75

2. A casting mold having a molding receptacle comprising a plurality of blocks of refractory material, said blocks being spaced 80 apart sufficiently to permit the expansion of the blocks and the escape of the gases from the metal but the spaces being of such width as to prevent the passage of the molten metal therethrough, the number of blocks and spaces corresponding to the extent of expansion of the material composing the 85 blocks.

3. A casting mold having a molding receptacle comprising a plurality of blocks of refractory material, separable flask sections 90 wherein said blocks are removably supported, the block supports of said flask sections being protected by said blocks against contact with the molten metal.

4. A casting mold having a plurality of chambered flask members provided with supports for a molding receptacle, and a plurality of blocks of refractory material forming said molding receptacle, said blocks being shaped to form a casting chamber and arranged at slight distances apart thereby 100 permitting gases to escape between said blocks and through the chambered flask sections and permitting the expansion of the blocks. 95

5. A casting mold comprising separable 105 metal flask sections, each of said flask sections carrying a plurality of blocks of refractory material, which blocks, when the flask sections are closed, form a casting chamber and prevent the flask members from 110 contacting with the molten metal.

6. A casting mold comprising separable metal flask members provided with inwardly extending supports, and a molding receptacle formed of blocks of refractory 115 material shaped to interlock with said supports and protect them from contact with the molten metal.

7. A casting mold comprising separable metal flask members having a molding receptacle formed of a plurality of sections 120 of refractory material detachably connected thereto.

8. A casting mold comprising a plurality of separable metal flask members each provided with a mold section formed of a plurality of separate blocks of refractory material detachably connected to said member, 125

1. said blocks forming, when said members are brought together, a casting chamber.
2. A casting mold comprising a metallic body formed of a plurality of separable members, each of said members being chambered and provided with inwardly projecting supporting means, said members having mounted upon their supporting means a plurality of blocks of refractory material adapted, when the members are brought together, to form a molding receptacle spaced from the metal walls of the body.
3. A casting mold comprising a plurality of hollow members provided with inwardly projecting supporting means, and a molding receptacle formed of a plurality of blocks of refractory material mounted upon said supporting means in such manner as to leave free space between the outer faces of said blocks and the corresponding walls of the members.
4. In a casting mold, a metal member provided with an inwardly projecting support, a plurality of blocks of refractory material mounted upon said support to form part of a molding receptacle, and detachable means for holding said blocks removably in place thereon.
5. In a casting mold, a hollow member provided with an inwardly projecting rib, a molding receptacle section comprising a plurality of blocks of refractory material mounted upon said rib, and a key plate detachably connected to said hollow member and engaging said blocks to retain them in position thereon.
6. A casting mold comprising a base member, end members, and a plurality of sides pivotally supported on said base member, each of said sides comprising two members hinged together and having a molding receptacle section of refractory material detachably connected thereto.
7. A casting mold comprising a base, two side members and two end members pivotally supported on said base, said members being provided with inwardly projecting supports for a molding receptacle, said receptacle being formed of a plurality of blocks mounted upon said supports.
8. A casting mold comprising a base, two sides and two ends pivotally mounted upon said base, each of said sides comprising two sections hinged together.
9. A casting mold comprising hinged side members and hinged end members, each of said members being formed with an inwardly projecting supporting bar and being provided with a removable key or guard plate detachably connected to said member, and a molding receptacle formed of sections of refractory material detachably mounted upon the supporting bars of said members and held in place by said keys or guard plates.
10. A casting mold comprising movable side and end members, a stationary member between said side members, and a molding receptacle formed of sections, certain of said sections being carried by the stationary member, and others of said sections by said side and said end members.
11. In a casting mold, a molding receptacle comprising a plurality of blocks forming a casting chamber, certain of said blocks being spaced apart to permit the expansion of the blocks during the casting operation.
12. In a casting mold, a molding receptacle comprising a plurality of blocks forming a casting chamber, certain of said blocks being spaced apart to permit the expansion of the blocks, the spaces between said blocks being of such width as to prevent the passage of molten metal therethrough while allowing for the escape of gases from said metal.
13. A casting mold comprising a plurality of separable flask members each provided with a mold section formed of a plurality of separate blocks, certain of said blocks in each section being spaced apart sufficiently to permit the expansion of the blocks in the section.
14. In a casting mold, a molding receptacle of refractory material having its walls provided with venting openings, said openings being of such width as to prevent the passage of the molten metal therethrough.
15. In a casting mold, a molding receptacle having its walls provided with a plurality of venting slots, said slots being of such width as to prevent the passage of the molten metal therethrough but permitting the escape of the gases.
16. In a casting mold, a molding receptacle having its walls slotted to permit expansion thereof and the escape of the gases, the slots in said walls being of such width as to prevent the passage of the molten metal therethrough.
17. A casting mold comprising a frame, and a substantially closed molding receptacle supported therein, said receptacle being formed of a plurality of blocks of refractory material.
18. A casting mold comprising a flask, and a molding receptacle supported therein, said receptacle being formed of a plurality of relatively movable blocks of refractory material.
19. A casting mold comprising a flask, and a separable molding receptacle supported within said flask with its walls spaced from the corresponding walls of the flask to form an air chamber therebetween, the walls of said flask being provided with one or more openings to permit the passage of air to and from said chamber.
20. A casting mold comprising a frame, and a molding receptacle supported therein,

said receptacle being formed of a plurality of spaced blocks of refractory material.

28. A casting mold comprising a metal flask, and a molding receptacle of refractory material supported within said flask and separable therefrom with its walls spaced from the corresponding walls of the flask to form an air-chamber therebetween, the walls of said flask being provided with openings to permit the passage of air to and from said chamber.

29. A casting mold comprising a metallic body formed of a plurality of separable members, each of said members being chambered and provided with inwardly projecting supporting means, said members having upon their supporting means a plurality of blocks of refractory material adapted, when the members are brought together, to form a molding receptacle spaced from the metal walls, and openings in said walls to permit the passage of air to and from the chambers in said members.

30. A casting mold comprising a metallic body formed of a plurality of separable

members, each of said members being chambered and provided with inwardly projecting supporting means, said members having upon their supporting means a plurality of blocks of refractory material adapted, when the members are brought together, to form a molding receptacle spaced from the metal walls, openings in said walls to permit the passage of air to and from the chambers in said members, and vent openings between said blocks.

31. In a casting mold, the combination with a flask, of a molding receptacle therein having its walls provided with a plurality of slots extending therethrough to permit the expansion of the walls and the venting of the gases from the receptacle.

32. In a casting mold, the combination with a flask, of a molding receptacle of refractory material supported within said flask and having its walls provided with a plurality of slots extending therethrough to permit the expansion thereof and the venting of the gases from said receptacle.

CLIFTON D. PETTIS.
